[57] CLAIM

The ornamental design for a beverage holder, as shown and described.

DESCRIPTION

The nature and intended use of the article being an ornamental design for a self-leveling beverage holder.

FIG. 1 is a top, front, right side perspective view of the beverage holder of the present invention;

FIG. 2 is a front elevational view of the beverage holder of FIG. 1;

FIG. 3 is a rear elevational view of the beverage holder of FIG. 1;

FIG. 4 is a left side elevational view of the beverage holder of FIG. 1, the right view being a mirror image thereof;

FIG. 5 is a top plan view of the beverage holder of FIG. 1; and,

FIG. 6 is a bottom plan view of the beverage holder of FIG. 1.

The broken lines showing of a bottle with insulating wrap in FIG. 1 is for illustrative purposes only and form no part of the claimed design.
